 United States Hoffman Machinery Corporation,
 New York, N. Y., a corporation of Delaware

Application February 24, 1931. Serial No. 517,979

28 Claims. (Cl. 68—9)

This invention pertains to presses and more particularly to those employed for pressing garments or fabrics.

More specifically, the invention relates to a power actuated press wherein a constantly operating motor is employed to transmit movement to the movable pressing element, in the closing, heavy pressure applying, and opening movements of said movable pressing element.

10 I am aware that, broadly considered, presses utilizing means to effect such results have been produced. The present invention, however, has for one of its main objects the reduction to a minimum of operator fatigue. One means to this end resides in the provision by which the head, or movable press element, may be closed to pressing relation, but not to exert heavy pressure, through the actuation of operator operated means such as a foot lever which controls the power means, including a friction clutch employed for this purpose. This friction clutch is again brought into use automatically for driving the press head to its open position following the release from heavy pressure.

25 Another means for reducing operator fatigue resides in mounting a lever on the head of the press for bringing the heavy pressure applying mechanism into operation, which lever, when the press is closed, is brought to a convenient position where it may be manipulated, and preferably in an upward direction, by the operator. When the head is brought to its heavy pressure position the control means, brought into operation by said lever, comes to rest and so remains until the lever is again actuated to release the head from heavy pressure. This lever, furthermore, has a novel feature in that it may be so applied to presses equipped with head steaming valves that it may serve the dual purpose of a steam valve handle 30 and also as the means for bringing the pressure applying mechanism into operation.

Another object of the present invention is to make the foot operated controlling means for the friction clutch inoperative when the press head reaches its wide open position should the operator be standing on the clutch operating pedal when releasing the head from pressure and thus prevent an unanticipated descent of the head should the operator be arranging the goods upon the pressing surface.

A still further object of the invention resides in the utilization of means whereby a two speed operation is effected, to wit:—a fast speed employed when the friction clutch is connected with the power means, that is, when the press head is

being raised or lowered, and a slow speed when the heavy pressure is being applied. By this arrangement a most efficient utilization of the power input is realized.

With these and other objects and advantages 60 in view, as will appear in the following specification, reference will be had to the annexed drawings wherein:

Figure 1 is a side elevation of a press in full open position with parts broken away and in section and embodying my invention;

Figure 2, a similar view with the head lowered to that position where the final or heavy pressure exerting mechanism may come into operation, the dotted lines indicating full pressure 70 position of the parts;

Figure 3, a vertical longitudinal sectional view illustrating the main operating shaft and the various associated elements;

Figure 4, an end elevation of the friction clutch 75 and operating connections, the parts being in that position where the head has been lowered through the friction clutch to the full line position of Figure 2;

Figure 5, a detail sectional view of the coupling 80 employed in connection with the friction coupling;

Figure 6 a top plan view of the housing or casting for the various driving and control elements (gears, cams, etc.) and the various rocker arms 85 and levers;

Figure 7, a transverse vertical section taken on the line VII—VII of Figure 3, the parts being in that position which they assume when the head is fully elevated (Figure 1); 90

Figure 8, a detail perspective view of a weighted rocker arm or lever and a cooperating member;

Figure 9, a detail view of such lever illustrative of the lost motion connection between the parts;

Figure 10, a transverse vertical sectional view 95 taken on the line X—X of Figure 6, the parts being shown in that position where the head is fully closed and under final heavy pressure;

Figure 11, a view taken on the line XI—XI of Figure 6, with the parts in a position where release of final heavy pressure has started, the cams being slightly advanced over the position shown in Figure 10;

Figure 12, a vertical sectional view taken on the line XII—XII of Figure 6; 105

Figure 13, a perspective view showing in detail certain of the parts associated with the means for initiating the final heavy pressure and likewise for operating the head steaming valve, the actuating lever being omitted; 110

Figure 14, a side elevation of such parts with the lever in position, together with certain of the actuating connections for bringing about heavy pressure;

5 Figure 15 a front elevation of the lever and associated parts;

Figure 16, a detail perspective view of the mechanism employed in conjunction with the friction clutch utilized for raising and lowering the head;

10 Figure 17, a detail horizontal sectional view illustrative of certain parts of the mechanism for applying or releasing the friction clutch;

Figure 18, a perspective view of one of the 15 shafts supporting two arms or levers and other elements, the first arm being that which is associated with a positioning cam which controls the position of the second arm that in turn functions to position and withdraw the locking pin employed to lock one element of the gear train and to thus impart motion to the main shaft;

Figure 19, a sectional view on the line XIX—XIX of Figure 22 showing one element of one 25 of the cams which are supported by the pins or axles of the planetary gears employed in the gear train;

Figure 20, a similar view, on the line XX—XX of Figure 23, of the companion member, said 30 members shown in Figures 19 and 20 being secured together and embracing between them the pins or axles just referred to;

Figure 21, a face view of the element shown in Figure 20 as seen from the left hand side thereof;

35 Figure 22, a like view as seen from the right hand side of Figure 19; and

Figure 23, a face view of the cam member shown in Figure 20 as seen from the right hand side of said Figure.

40 As will be appreciated, the press is of the lever type wherein the head is moved toward and from the buck.

In the drawings, 1 denotes the base of the 45 machine upon the forward upper portion of which is mounted the usual U-piece 2 which forms the support for the buck 3. At the rear the frame is provided with an upward extension 4 to which is pivotally connected a head lever 5, the pivotal shaft or connection being denoted by 6. A head 50 7 is secured to the forward end of the lever 5.

At the rear end of the head supporting lever 5 there is pivotally mounted a bell crank lever 8, the lower short arm of which is in turn pivotally connected to the upper link 9 of a toggle, 55 the lower member of such toggle being denoted by 10 and being pivotally connected at its lower end to a fixed portion of the frame. A spring 11 connected to the toggle elements tends to collapse the toggle and draw the rear end of the head lever downwardly, thus opening the press.

To the upper longer end of the elbow lever 8 is attached a spring box 12 and from said box there extends a rod 13 which passes through a fixed cross bar 14 extending between the bifurcated forward end of the head carrying lever 5. A hand wheel 15 is connected to the rod forward of the cross bar and by turning said wheel the elbow lever is rocked and consequently the effective action of the toggle with reference to the lever 5, may be regulated. This arrangement forms no part of the present invention but forms the subject matter of my prior application Serial Number 473,020, filed August 4th, 1930.

As above noted, the press is designed to be 75 operated by power. To this end a constantly

rotating electric motor 16 is employed, the shaft whereof may carry a balance wheel (not shown) mounted in a housing 17. The shaft extends outwardly therefrom into a supporting housing and casing denoted generally by 18 (see more particularly Figures 3 and 6 for the latter).

80 Secured to the shaft is a worm 19 which is in constant mesh with a worm gear 20. The hub 21 of said gear is keyed to the extended hub 22 of a bevel or sun gear 23. The hub 22 finds its bearing upon a bearing sleeve 24 mounted upon the main power transmitting shaft 25, which latter is supported in suitable bearings carried by the casing 18.

85 Gear 23 meshes with a series of planetary gears 26 and the latter in turn are in mesh with a second bevel or sun gear 27. This latter finds its bearing upon a sleeve 28 mounted upon the shaft 25. The gears 26 are supported upon axles or spindles 29 extending outwardly from a hub 25 or spider frame 30 keyed to the shaft 25. A locking screw 31 (Figure 3) may also be employed to assist in holding the spider frame in place.

90 Keyed to the outwardly extending hub of the gear 27 is a locking ring 32 having a series of spaced teeth 33 formed about its periphery (see more particularly Figure 10). This ring underlies a bolt 34, the lower end whereof is chamfered and so formed that it may pass in between a pair of the teeth 33 and thus arrest movement of the gear 27 and, as a consequence, impart motion through the associated gears to the shaft 25. This arrangement of planetary gearing effects a two to one reduction between the worm gear 95 20 and the shaft 25 resulting in a very efficient utilization of the power input. This is amplified by the utilization of the toggle above described which is moved toward straightened position by a pitman 35 pivotally connected to a combined 105 cam and crank disk 36 secured to one end of shaft 25. As will be appreciated, shaft 25 is normally free of any driving connections, and, consequently, the head 7 may be raised or lowered by hand for any desired purpose.

110 120 Primarily, however, this machine is designed to be operated through power mechanism, both in the raising and lowering of the head and such mechanism will now be described.

Surrounding shaft 25 to the right of sleeve 24 125 (Figure 3) is a sleeve 37 upon which in turn is mounted a hub-like element 38 (Figure 5), the enlarged end whereof is toothed as at 39 to engage notches 40 in the hub 21 of gear 20.

Member 38 has mounted thereon one race 130 member 41 of a ball bearing, the other race element, designated by 42, finding its bearing in a flange 43 extending inwardly from a supporting plate 44 secured to housing 18.

The member 38 at its right, as seen in Figures 135 3 and 5, is threaded and the hub of a plate 45 is screwed thereon, said plate being provided with a plurality of outwardly extending fingers 46. Said fingers freely pass into notches 47 formed in a plate 48 provided with a hub 49 in which 140 latter is mounted a thrust ball bearing designated generally by 50, the race elements whereof are held in place by a surrounding band 51. Shaft 25 at this end is provided with a plurality of splines 52 held in place by a washer 53 and 145 screw 54, see Figures 3, 4 and 12.

A hub 55 extending from a plate 56 encircles shaft 25 and is formed with slots or grooves into which the splines freely extend, thus allowing plate 56 and hub 55 to be shifted longitudinally 150

of the shaft and splines. Plate 56 has secured to its opposite faces, adjacent its periphery, friction elements 57 and 58 which normally stand in spaced relation to the plates 45 and 48 and form therewith a friction clutch, one element whereof, consisting of the members 45, 48 and 50, is constantly rotated through the construction above set forth.

The clutch is enclosed in a housing 59 (Fig. 3) 10 and a rocker shaft 60 is vertically disposed therein, the shaft at its lower end being seated in a bearing 61 while its upper end extends through a bearing member 62 mounted in the upper portion of the housing 59. Shaft 60 has formed upon it, or secured thereto, two outwardly extending fingers 63 and 64 which stand in alignment with the outer element of the thrust bearing 50, said fingers acting, when the shaft is rocked or partially turned, to force the bearing 50, and 15 consequently plate 48, inwardly so that the friction elements 57 and 58 respectively engage the constantly driven plates 45 and 48. As a consequence motion is imparted to shaft 25 through splines 52 and the combined cam and crank disk 36 will be rotated, straightening or breaking the toggle as the case may be through pitman 35.

The clutch and its associated parts are designed to be operated and rendered effective (1) through a foot lever for lowering the movable 20 press member to that position where the final or heavy pressure exerting mechanism may be brought into operation and (2) through power means for driving the movable press member to its open position immediately following the release from heavy pressure.

Secured to the upper end of shaft 60 (Figs. 3, 4, 6 and 16) is an arm 65 in the outer end whereof is adjustably mounted a screw 66. One end of this screw is formed with a socket to receive the end of a plunger 67, the opposite headed end whereof works in a housing 68 and against a spring 69. The plunger and housing form in effect a yielding link or connection between the lever 65 and an arm 70 extending downwardly 40 from a collar 71 pinned to a shaft 72. Said shaft, as will be seen upon reference to Figure 6, is mounted in suitable bearings 73 and 74 formed in upward extensions of the casing 18.

Secured to the shaft 72, adjacent the bearing 50 74 (Fig. 6), is a collar 75 provided with an outwardly extending arm 76, the end whereof is bifurcated. This bifurcated end straddles the upper reduced portion of a plunger-like element 77 (Fig. 3) which works in a bearing sleeve 78 55 mounted in the upper portion of the casing 18. Extending downwardly from the collar 75 is an arm 76^a between which and a fixed portion of the casing 18 is interposed a spring 76^b (Fig. 7) which has a tendency at all times to rock the collar 75 60 and thus force the plunger 77 downwardly. At its lower end the plunger is provided with a roller 79 which overlies a cam element 80 having a high effective portion 81 which latter, when it rides under the roller, tends to elevate the same and 65 move the plunger upwardly. As a consequence the shaft 72 will be rocked counter-clockwise.

Secured to the shaft 72 outward of the bearings 73 is a sleeve-like element 82 (Fig. 8) having an outward extension 83 semi-circular in contour, 70 the face 84 whereof is designed to cooperate with an angularly disposed face 85 formed upon a lever 86 loosely mounted upon the shaft 72.

The lever 86 is counterweighted, as at 87, so that normally the faces 84 and 85 will be in contact. This arrangement of parts produces a lost

motion connection between the shaft 72 and the lever 86, the degree of which movement may be regulated by an adjustable stop screw 87^a (Fig. 3) underlying the same.

At its outer downwardly extending end the lever 86 is provided with a roller 88 which stands in alignment with one end of an elbow lever 89 pivotally connected at 90 to the lower end of an arm or lever 91. This latter lever is pivotally mounted upon a stub shaft 92 secured at one end (Fig. 17) in a boss 93 extending outwardly from an upwardly extending portion of the main frame 1.

Lever 91 has formed integral with its hub a projection 94 to which is pivotally connected the upper end of a draw rod 95 which at its lower end is pivotally attached to a foot lever 96 fulcrumed at 97. Said lever is normally raised by a spring 98 which underlies the same.

Lever or arm 89, which as above stated, is fulcrumed at 90 to the lower end of arm 91, is normally rocked counter-clockwise by a spring 99 and urges the roller 100 toward the edge of cam 36. The lower arm of the elbow lever 89 is also formed with a bearing surface 101 concentric with the pivot point 90 and likewise formed with an abutment or stop face 102. These faces are designed to coact with roller 88 carried by lever 86.

The parts just mentioned are employed to operate the friction clutch heretofore described 105 when the foot lever 96 is depressed, whereby the lever 91 is moved counter-clockwise from the position shown in Figures 1 and 7 to the position shown in Figures 2 and 4 in which latter the head has been moved downwardly through the action 110 of the friction clutch to a position where final heavy pressure may be exerted through the gearing when the same is rendered effective through the actuation of certain means under the control of the operator.

As will be seen upon reference more particularly to Figures 4, 10 and 11, the combined cam and crank disk 36 is provided with an outwardly extending stop lug 104 which coacts with a downwardly extending arm 105 (see also Figure 18), 120 which arm is formed integral with a hub 106 pinned or otherwise secured to a rocker shaft 107 supported in suitable bearings formed in the upward extensions 108 and 109 of the main housing 18.

Secured to the shaft 107, between its bearings, is a sleeve 110 (see Figure 18) provided at one side with an arm 111 to which is attached the upper end of a tension spring 112, the lower end of the spring being connected to a fixed portion of the 130 housing 18. The spring tends to rotate the sleeve 110 clockwise.

Extending outwardly from the opposite side of the sleeve 110 is an arm 113, the outer end whereof is bifurcated. Said bifurcated end receives the 135 upper reduced end of the bolt 34 (see more particularly Figs. 3 and 10). A nut 114 and washer 115 are mounted upon the upper end of the reduced portion and overlie the upper face of the bifurcated arm or lever 113. Underlying the arm 140 and encircling the reduced portion is a second washer 116 and encircling the stem and bearing against the underface of the washer and the main body of the bolt 34 is a coil spring 117. This arrangement provides a buffer or shock absorbing 145 means in case the parts are not properly positioned for one or another reason.

Formed integral with the sleeve 110 is a third outwardly extending arm or lever 118, the outer end of which is bifurcated and embraces the up- 150

per reduced end of a slide or plunger 119 mounted for reciprocation in a bearing 120 formed in or supported by the casing 18. This plunger at its inner end has secured to it a roller 121 designed to coact with the two cam projections or surfaces 122 and 123 (see more particularly Figures 21 and 23) formed upon a member or cam element 124. Said member 124 is likewise provided with a raised portion 125 which underlies the bolt 34 (see more particularly Figure 3) and positively holds the same in its elevated position while the head is being raised or lowered by hand or through the friction clutch. It also holds the bolt out of locking relation should the bolt connections, by any reason, be broken and thus prevents the closing of the press except and only when the head is brought down into pressing relation with the buck prior to the application of heavy pressure. The parts are so proportioned that when heavy pressure is to be applied through the gearing the raised portion 125 passes out of contact with the lower end of the locking bolt or plunger 34.

The member 124 and the member 80 are provided respectively with semi-circular seats 126 and 127, which, when the two elements are in position, embrace the axles of spindles 29 (see Figure 3) and are thus caused to rotate by reason of the connection of said members to the hub 30 which in turn is secured to the main operating shaft 25. The elements are secured together by screws 128 passing through suitable openings formed therein.

Connected to the member 105 (see Figures 1, 2 and 18) is a rod 129 which at its upper end is pivotally attached to a plate 130 (Figure 14) fulcrumed upon a shaft 131 secured in the main frame of the machine. To the upper portion of said plate 130 there is pivotally attached a link 132 which is likewise attached at its upper end to a bell-crank lever 147 fulcrumed, upon the upward extension of the main frame, as at 148. Extending forwardly from the upper end of this bell-crank lever is a draw rod 149, which at its forward end (see more particularly Figures 13, 14 and 15) is connected through a clevis 150 to the lower end of a lever 151 fulcrumed upon a pin or shaft 152 mounted in the upper portion of a bracket, denoted generally by 153, the lower end whereof is secured in place between the ordinary jam nuts 154, 155 mounted upon the upper end of the usual head steaming valve.

Pivoted upon the shaft 152 and extending toward the forward portion of the press is a hand lever 156 which has a pair of lugs 157 and 158 extending laterally therefrom on opposite sides. The lug 157 underlies an overhanging portion of the lever 151 so that as the hand lever 156 is pushed upwardly the lug 157 will rock the lever and draw the rod 149 forwardly and actuate the other parts allied therewith, as will appear later on.

Pivoted on the pin 152 is a lever 159, the forward end of which stands in the path of the lug 158 while the rear end of the lever is provided with an opening through which stem 160 of the head steaming valve extends as is usual.

A spring 161 normally draws this lever 159 downwardly and closes off the steam valve as is usual. If desired the steam valve may be opened through means other than the lever 156, as for instance through a lever 162, fulcrumed upon the shaft 152 and overlying the forward end of the lever 159. Said lever 162 may be attached to a hand lever or a foot lever as desired, where-

by it may be operated to produce a steaming action.

As will be seen upon reference to Figure 2, the usual handle employed to draw the head downwardly and into contact with the buck or the goods imposed thereon is present and is designated by 163.

From the foregoing it will be appreciated that the press involves a two speed power arrangement, first, fast speed through the friction clutch 85 for bringing the press head into pressing position and, second, slow speed power multiplying mechanism for applying heavy final pressure.

Operation

The operation of the press may be briefly stated as follows, it being kept in mind that the press may be closed either by hand or through actuation of the friction clutch, one element of which is constantly rotated by the motor, and will be opened through power means as well as by the springs 11. Also that when it is closed, either through power or by hand, heavy pressure may be exerted upon the goods through power multiplying mechanism, to-wit:—the gearing and the 100 toggle.

Assuming that the parts are in the position shown in Figures 1 and 7 with the head fully elevated, and it is desired to lower the head through the operation of the friction clutch, the operator 105 will depress the foot lever 96 and through the rod 95 draw the arm 94 downwardly and likewise impart a counter-clockwise movement to the arm or lever 91. This throws the arm or lever 89 to the right (Fig. 7) and forces the face 101 thereof 110 into contact with the roller 88 carried upon the arm 86. Movement of the arm 86 in a counter-clockwise direction rocks the shaft 72 in a like direction,—this by reason of the fact that the faces 84 and 85 are in contact with each other 115 during such movement. Arm 70, which is formed integral with the sleeve 71 (which latter is pinned to the shaft 72), is also moved counter-clockwise.

Through the connections interposed between the arm 70 and the lever 65 (Figures 4 and 5) the 120 friction clutch, one member of which is rotated at all times, is brought into operation. This will lower the head by actuating the combined cam and crank disk 36, the parts then coming to the position shown in Figures 2 and 4, and the stop 125 104 contacting the lower end of the lever 105 and arresting further movement of the disk 36 and pitman 35. The friction clutch, however, is still operative and slips by reason of the fact that roller 88 is still in contact with the face 101 130 and thus holds the parts in clutch actuating relation until heavy pressure is applied or the head released.

If the head is not locked under heavy pressure and the foot is removed from the treadle lever 96 135 the parts just mentioned, due to the spring 99, will return to normal position while the main springs, as 11, on the press will pull the head back to its wide open position. When, however, after bringing the head into pressing relation as previously described, it is desired to apply heavy pressure the operator, while holding the head down by the handle 163 (as he would naturally do although such holding is not necessary), pushes up on the hand lever 156 and in so doing, 145 through the connections before described, draws the arm 105 out of contact with the stop lug 104 upon the element 36. At the same time the member 113 is rocked downwardly and the bolt 34 enters one of the recesses between the teeth 33 of 150

the member 32 (Figure 12) thereby causing the gearing to come into operation to drive the shaft 25 and apply heavy pressure through the power multiplying gearing, the shaft and the toggle mechanism. At the same time the cam elements 80 and 124 are caused to rotate and the projection 122 moves from the roller 121 and allows such roller to drop into the valley or recess intermediate said projections 122 and 123 at which time, through the connection of the parts, the spring 112 will draw the bolt 34 upwardly and disrupt the connection between the gearing and the shaft 25. The press may remain in this position with the heavy pressure on as long as desired.

When the parts are in the position where heavy pressure may be applied through the gearing, and the arm 105 is moved out of contact with the stop 104 as above noted, the combined cam and crank disk 36 will rotate and the nose X thereof will contact the roller 100, swinging the arm 89 outwardly and permitting the roller 88 to move upwardly into the position shown in Fig. 10. This movement releases the friction clutch, allowing the shaft 60 to rotate and withdraw pressure from the shaft 60 to rotate and withdraw pressure from the movable frictional element 48. As the combined crank disk and cam 36 continues its rotation and the roller 79 rides onto the cam 81 the lever or arm 76 will be raised and the shaft 72 rotated counter-clockwise, but owing to the lost motion connection between the shaft 72 and the lever 86 the lever 86 will not be actuated. The weight 87, of course, tends to move the lever 86 clockwise and to hold the face 85 out of contact with the face 84 when the parts are in the position shown in Figure 11.

When the heavy pressure is to be released the operator again pushes up on the hand lever 156, thereby raising the roller 121 from the depression between the projections 122 and 123 while at the same time throwing the bolt 34 down into one of the notches between the teeth 33, again locking the gearing into driving relation with the shaft 25. This locking relation will be maintained so long as the roller 121 rests upon the member 123, and thus the head is initially opened through gear operation. As the cams continue their rotation the roller 79 comes into contact with the cam face 81 raising the plunger 77 and rocking the lever 76 upwardly thereby again bringing the friction clutch into operation through the arm 70, the arm 65, and the interposed connections between 70 and 65. The frictional drive will be held in operative relation by the cam surface 81 until the head is fully raised, at which time the cam surface moves from under the roller 79 and allows the parts, urged by the spring 76^b, to come to rest.

Should the operator have kept the foot lever 96 depressed during the opening movement of the press head, as just described, the friction clutch actuating mechanism controlled by the foot lever will be in the position as indicated in dotted lines in Figure 7. From this it will be noted that the roller 100 is out of engagement with the cam 36 and arm 89 is out of engagement with the roller 88, and consequently the arm 86. This arrangement of parts is designed to prevent an unanticipated descent of the head at the end of the head opening cycle, should the operator inadvertently keep the foot lever 96 depressed during the power actuated opening of the press head. It therefore becomes necessary for the operator, when he again desires the friction clutch to be brought into operation to lower the head, to raise his foot from the foot lever and

again depress it. When the operator's foot is raised from the foot lever 96 the arms 91 and 89 are restored to the full line position shown in Figure 7 through the action of springs 98 and 99.

As above noted, there is present in the machine as illustrated a head steaming valve and this is utilized in forming a support for the actuating lever, which lever has the dual purpose or function of bringing into operation the heavy pressure applying means and the steaming valve. Should the press be constructed without such head steaming valve the bracket 153 would, of course, be directly secured to the head.

Although not shown, the usual vacuum-producing means may be utilized.

The presence of the handle 163, in addition to the upwardly moving lever 156, will, as above noted, naturally cause the operator to grasp both handles. This is particularly so when he is standing on the treadle lever 96 or on the steam vacuum levers (not shown);—this with a view of steadyng himself.

The machine is also capable of being employed to pat the goods imposed upon the buck and where silks and such fabrics are being treated the heavy pressure applying mechanism may not be brought into operation.

What is claimed is:

1. In a garment press, the combination of two pressing members, one movable relatively to the other; a continuously operating motor; a friction clutch; gearing independent of said clutch; a shaft associated with said clutch and gearing; connections between the shaft and the movable pressing element for moving the latter; and means for rendering either the clutch or the gearing effective to drive the shaft.

2. In a power operated garment press, the combination of two pressing members, one movable relatively to the other and adapted to be moved toward final pressing position at a speed relatively rapid as compared to the speed of the final pressing movement; constantly operating and non-reversing power actuated means for imparting such rapid closing movement to the movable pressing element; power multiplying means for applying relatively heavy pressure to the movable pressing element after it is brought into initial pressing relation with the other member; and means for automatically arresting movement of the power multiplying means to maintain the pressure applying position of the press.

3. A press as set forth in claim 2, wherein the power actuating means for closing the press includes a friction clutch.

4. A press as set forth in claim 2, wherein the power multiplying means for applying heavy pressure includes a gear reduction train and a toggle.

5. In a garment press, the combination of a pair of pressing members, one movable relatively to the other; a motor; a friction clutch associated with the motor; means acting at all times to move the clutch to inoperative position; gearing also associated with the motor and normally free of any driving connection therewith; means acting to maintain such relation between said gearing and motor; a toggle connected with the movable pressing member; a shaft; connections between the shaft and toggle to actuate the latter; operator operated means for bringing the clutch into driving relation with the shaft; and similar means for rendering the gearing effective to apply heavy pressure upon the movable pressing element.

6. A press as set forth in claim 5, wherein the means for rendering the clutch effective includes foot actuated means.
7. A press as set forth in claim 5, wherein the means for rendering the gearing effective includes a lever mounted upon the movable pressing member.
8. In a garment press, the combination of a buck; a head cooperative therewith; frictional driving means for moving the head into pressing relation with the buck; and motor driven means for applying heavy pressure to the head when the parts are so positioned.
9. In a garment press, the combination of cooperative pressing elements, one of which is movable; a continuously operating motor; a friction clutch, including two cooperative elements, one element whereof is continuously driven by the motor and the other element whereof is normally free; a toggle interposed between a fixed portion of the press and the movable pressing element; a shaft; connections between the shaft and toggle; connections between said shaft and the continuously driven element of the clutch; and means under the control of the operator to render the clutch effective to close the press through straightening of the toggle.
10. In a garment press, the combination of two pressing members, one movable relatively to the other; a constantly operating motor; a friction clutch embodying two cooperative elements; connections between said clutch and the motor for continuously driving one element of such clutch; a shaft with which the other element of the clutch is connected, operator operated means for bringing the clutch elements into operative relation to drive the shaft; and means interposed between said shaft and the movable pressing element for shifting the latter into closing position.
11. In a garment press, the combination of two pressing members, one movable relatively to the other; a toggle interposed between the movable member and a fixed portion of the press; a shaft; connections intermediate the shaft and the toggle for operating the latter when the shaft is rotated; a motor; a friction clutch embodying two elements, one of which is constantly driven by the motor; means under the control of the operator for establishing connection between the other clutch element and the shaft; differential gearing, one element whereof is constantly rotated by the motor, said gearing being mounted upon the shaft and normally free of any driving connection with the shaft; and means under control of the operator for rendering said gearing effective to impart rotary motion to the shaft.
12. In a garment press, the combination of two pressing members; one movable relatively to the other; a toggle connected to the movable member and a fixed portion of the press; a shaft; means interposed between the shaft and the toggle for operating the latter; a motor; a friction clutch for driving the shaft, one member of which clutch is constantly rotated by the motor; means under the control of the operator for bringing said driven element of the friction clutch into driving relation with the shaft; a stop for arresting movement of the toggle when the movable element has been brought into pressing relation with the other pressing member while permitting the clutch to slip; and means independent of the clutch under the control of the operator for exerting final heavy pressure between the pressing member.
13. In a garment press, the combination of a main frame; a buck mounted thereon; a head; a head-carrying lever fulcrumed on the frame; toggle means interposed between a fixed portion of the frame and said lever; a shaft supported by the frame of the machine; a pitman connected to the toggle; a crank disc carried by the shaft and connected to the pitman, said crank disk having a cam surface formed upon its periphery; a motor; a frictional clutch including two elements, one element whereof is driven by said motor and the other element whereof is carried by the shaft; means under the control of the operator for rendering said clutch effective to impart rotary motion to the shaft, said means embodying a lever supported for movement toward and from the cam surface aforesaid and provided at its lower end with a roller, said lever likewise having stop faces formed adjacent its lower end; an arm fulcrumed upon a second shaft, said arm likewise having a roller mounted in its outer end and designed to coact with the stop faces aforesaid; a second cam mounted upon the first named shaft; a plunger mounted for endwise movement in line with said cam; a lever connected to the second shaft, the outer end of the lever bearing upon the upper portion of the plunger; a lost motion connection between said last named shaft and the arm fulcrumed thereon; and a weight acting to move the free end of the arm upwardly, the surface on the crank disk and that of the other cam being so angularly disposed about the shaft upon which they are mounted that the clutch will be thrown out of operation when the head is fully opened and prevented from further operation until the operator releases the clutch-engaging means prior to again actuating said means.
14. In a garment press, the combination of a main frame; a buck mounted thereon; a head; a head-carrying lever; a toggle connected to said lever and to the frame; a constantly operating motor; a main driving shaft; a normally free friction clutch transmitting motion from the motor to the shaft when the clutch is rendered effective; a combined cam and crank disk secured upon the driving shaft; a pitman interposed between said disk and the toggle; and operator operated means for rendering the clutch effective, said means embodying an element cooperative with the cam aforesaid to prevent reengagement of the clutch which is automatically released when the head is fully opened until said operator operated means has been released.
15. In a garment press, the combination of a main frame; a buck mounted thereon; a head; a head-carrying lever fulcrumed on the frame; a toggle interposed between the frame and lever; a motor; a main driving shaft; a clutch, one element thereof being constantly driven by the motor and the other splined to the driving shaft; a rocker shaft supported by the frame; a lever pivoted on said rocker shaft having one end thereof weighted; a roller carried at the other end, said lever having a stop shoulder or face formed thereon; a coacting stop shoulder carried by and movable with the rocker shaft, said shoulders being free to move apart to produce a lost motion connection; an elbow lever supported adjacent the lever aforesaid, said elbow lever having stop faces formed on the end of its inner arm adapted to coact with the roller of the first lever; a roller mounted upon the inner end of the elbow lever; means for rocking said elbow lever and moving its inner end inwardly; a cam surface engaging said last named roller to move it and the lever

- outwardly to free the other lever; and means interposed between the rocker shaft and the clutch element splined to the drive shaft to move such element into operative relation with the other 5 clutch member.
16. In a garment press, the combination of a main frame; a buck thereon; a head; a head-carrying lever fulcrumed on the frame; a toggle interposed between the lever and frame; a driving 10 shaft; a crank disk; a pitman interposed between said disk and the toggle; a constantly rotating motor; planetary gearing including two sun gears, one driven by the motor; an element secured to the shaft upon which the planet gears 15 are mounted; a lever mounted on the head; and connections between the lever and the second sun gear for arresting rotation of the latter and thereby imparting motion to the driving shaft through the planetary gears and the element 20 upon which they are mounted.
17. A press as set forth in claim 16, wherein means is provided for automatically arresting movement of the driving shaft to maintain pressure applying position of the parts.
18. A press as set forth in claim 16, wherein means is provided for releasing the connections 25 between the lever and the second sun gear when the parts come to rest in pressure exerting position.
19. A press as set forth in claim 16, wherein the lever on the head has an upward movement to cause it to function.
20. A press as set forth in claim 16, wherein means is provided for releasing the connections 30 between the lever and the second sun gear allowing the parts to come to rest and in position to be again set in motion by pushing the lever upwardly.
21. A press as set forth in claim 16, wherein a friction clutch is employed to close the head upon the buck, the crank disk is provided with a stop lug, and the connections between the lever and the sun gear embody an arm cooperative with the 40 stop.
22. In a garment press, the combination of a main frame; a buck; a head; a head-carrying lever fulcrumed on the frame; a toggle interposed between the lever and frame; a drive shaft; a pitman driven from the shaft and connected to 45 the toggle; a constantly operating motor; a friction clutch, one element whereof is driven at all times by the motor, the second element of the clutch being splined to the shaft; a foot lever; connections between said lever and the second 50 clutch element acting to bring the members into driving relation; a cam rotatable with the shaft and likewise cooperative with said connections to hold the clutch elements in driving relation; planetary gearing associated with the shaft, the 55 supports for the planet gears being secured to and movable with the shaft and one of the sun gears being constantly driven by the motor; a toothed member rotatable with the second sun gear; a reciprocating bolt or pin mounted for engagement with said member; a second cam rotatable with the shaft, said cam having two marginal projections with a valley there-between; a plunger mounted for endwise movement toward and from said second cam; a rocker shaft; a 60 sleeve secured thereto; an arm extending outwardly to each side of said sleeve and cooperatively connected to the bolt and the plunger re- 65 spectively; a hand lever mounted on the head; connections between said lever and the rocker shaft; and means for normally rocking the shaft in opposition to the movement imparted thereto by the hand lever.
23. A press as set forth in claim 22, wherein the driving shaft is provided at one end with a combined crank disk and cam, said disk being connected to the pitman and likewise provided with a stop lug coacting with an arm forming part of the connections between the hand lever and the rocker shaft, the cam cooperating with an element of connections between the foot lever and the second clutch element.
24. In a power operated garment press, the 90 combination of two pressing members, one movable relatively to the other and adapted to be moved toward final pressing position at a speed relatively rapid as compared to the speed of the final pressing movement; a constantly operating non-reversing motor; means interposed between the motor and the movable pressing member for imparting said rapid closing movement thereto; and means likewise interposed between said motor and the movable pressing element for there- 95 after imparting a relatively slow motion to the head to apply a final heavy pressure.
25. In a power operated garment press, the combination of two pressing members, one movable relatively to the other and adapted to be 100 moved toward final pressing position at a speed relatively rapid as compared to the speed of the final pressing movement; power actuated means including a constantly operating non-reversible motor for imparting said rapid closing movement 110 to the movable pressing element; and power actuated means likewise actuated by the motor for applying relatively heavy pressure to the movable pressing element, said means imparting movement to the movable element, said movement 115 being relatively slow as compared to that of the closing movement.
26. In a garment press, the combination of a 120 buck; a head movable relatively thereto; a head steaming valve carried by the head; power actuated means for applying pressure to the head; a lever cooperative with the steaming valve to actuate the latter when the lever is moved in one direction; and means interposed between the lever and the power means for throwing the lat- 125 ter into operation when the lever is moved in the opposite direction.
27. A press as set forth in claim 26, wherein the lever is moved upwardly to throw the power means into operation.
28. In a garment press, the combination of a 130 buck; a head; a head steaming valve carried by the head; a bracket supported by the head steaming valve; a lever fulcrumed adjacent said valve, said lever being provided with oppositely disposed laterally extending projections; a lever having one end associated with the stem of the head steaming valve, the opposite end thereof underlying one of said projections; a third lever, one end of which overlies the other projection; power 135 operated means for closing the head upon the buck; and a connection between the third lever and said power operated means for bringing the latter into operation when the first named lever is moved upwardly.

WILLIAM STROBRIDGE.
